SECURITY COMMUNICATION SYSTEM

Constantin S. Szegho, Chicago, Ill., assignor to
The Rauland Corporation, Chicago, Ill., a corporation of Illinois

Application November 13, 1943, Serial No. 510,129

9 Claims. (Cl. 178—22)

1

This invention relates to new and useful improvements in secret communication systems and particularly in such systems which employ cathode ray tubes.

According to the present invention, a cathode ray tube is used in a system of communicating intelligence merely to indicate an ordinate sequence of light spots on a pattern. If a given pattern is available only at the transmitting and the receiving ends, the secrecy of the transmission is assured, since to all others the signals would represent only a meaningless sequence of spots. The letters of the alphabet can be impressed on the pattern avoiding thus the coding and decoding of messages.

In the drawing:

Fig. 1 diagrammatically represents one embodiment of this invention as applied to a receiver;

Fig. 2 represents one possible form of letter pattern employed in the practice of my invention;

Fig. 3 represents an alternative embodiment of my invention in a receiver;

Fig. 4 shows one possible arrangement of a transmitter for practicing my invention; and

Fig. 5 shows a detail of one form of keyboard which may be used at a transmitter according to my invention.

In Fig. 1 the reference numeral, 1, denotes a cathode ray tube having the customary fluorescent screen 2. The end of the tube is covered by a mask 3. A light spot produced on the screen 2 by an electron beam originating at the electron gun 4, is projected through the mask 3, and through a suitable optical system 5, upon a projection screen 6. Assuming that a predetermined pattern is impressed on the mask 3, e. g. by having certain portions thereof cut away, a replica of this pattern will appear upon the projection screen 6. A person viewing the effect of signals in any other cathode ray tube which is not equipped with a similar mask, will obtain only a meaningless sequence of signals.

A simple pattern is illustratively shown in Fig. 2, in which the letters of the alphabet appear in irregular sequence and each letter is repeated several times at the same or different places. The luminous spot will pick out in sequence first one and then another letter of the alphabet and thus convey the information desired.

In the arrangement shown in Fig. 3, the pattern is directly impressed upon a projection screen 6'. The different elements of the pattern are illuminated by projecting thereon through an optical system 5' light spots produced by the beam originating from the cathode ray tube 1'.

2

As above stated, the same pattern is used at the transmitting as at the receiving end, and the patterns used may be changed in any suitable prearranged manner. At the receiver, the travel of the spot over the screen of the cathode ray tube can be controlled in accordance with any suitable scanning procedure. Since the definition of this kind of intelligence need not be high, if the object be scanned with the employment of as much as 40 lines, the entire alphabet in the receiver can be repeated at least 30 times in the pattern used, with retention of sufficient clarity.

Additionally, the electron beam within the receiving tube may be moved along a straight line or over a simple geometrical path, by applying the incoming low frequency signals to the customary deflecting plates or coils which control such beam movement.

One possible arrangement suitable for transmitting such signals is shown in Fig. 5. A keyboard 10, like that of a typewriter, has keys such as the one shown at 11, as representing the letter A, which keys will each, when depressed, cause respective voltage drops E_x and E_y across two resistors 15 and 16 (Fig. 5), which are arranged so as to be respectively of values of resistance proportional to the distance of the key from the edge of the keyboard 10. The two voltages so derived can be used either to modulate two separate carrier waves, or can be used to modulate the same carrier wave. The signals so transmitted can be separated in any convenient manner, as well known in the art.

Alternatively, a camera tube 19, may be used in the transmitter and then the intelligence can be transmitted by illuminating a predetermined point of the pattern whenever a key is actuated.

As shown in Fig. 4, when a key 11', like the one representing the letter A on keyboard 10, is depressed, then through a suitable system of levers, diagrammatically illustrated at 12, a shutter 13 opens a corresponding aperture 14 in a screen 14', on which screen the pattern wanted is defined by a series of similar small apertures. The light rays 17, derived from any suitable source 18, will then traverse aperture 14 and will be recorded at a corresponding point of the scanning field of camera tube 19, having passed through a suitable optical system, 20, before reaching camera tube 19.

What is claimed is:

1. Secrecy communication system including means for transmitting electrical impulses corresponding to a predetermined position of the spot

of a cathode ray tube, means for receiving said impulses, a cathode ray tube actuated by said received impulses, a code screen having a predetermined pattern of characters and means for optically superposing said code screen upon the screen of said cathode ray tube, whereby said predetermined position of said spot relative to said code screen corresponds to a given character upon said code screen, each spot position being discrete and unconnected with any other spot position.

2. System according to claim 1, in which said code screen is of the cut-out type and is placed directly over the outer surface of said cathode ray tube screen.

3. System according to claim 1, in which said code screen is formed of material capable of transmitting light in at least a translucent manner, has said pattern of characters impressed thereupon in opaque form and is placed directly over the outer surface of said cathode ray tube screen, whereby said spot illuminates and renders visible a predetermined character.

4. System according to claim 1 in which said means for transmitting electrical impulses include a keyboard having a plurality of contact-making keys thereupon, two resistors connected to each key, means to produce voltage drops across said resistors when said key is depressed, whereby the values of said respective voltage drops can be used to determine the locus of a point on a surface, and whereby said resistors function similarly to a set of coordinates and determine the two dimensional position of said spot at the cathode ray tube, each key being connected to resistor of a value different from any other resistors in the same row of keys.

5. System according to claim 1, in which said code screen is physically discrete and separated from said tube screen, and also including an optical projection system, whereby said spot is opti-

cally projected upon said code screen at a predetermined point thereof.

6. System according to claim 1, in which said means for transmitting electrical impulses include a substantially rectangular keyboard having a plurality of contact-making keys thereupon, two resistors, extending vertically and horizontally from each key and having electrical values respectively equal to the abscissa and ordinate of the key to which they both are connected, and means for deriving from said two resistors electrical impulses determining at the cathode ray tube the two-dimensional position of said spot.

7. Secrecy communication system including means for transmitting electrical impulses corresponding to a predetermined position of the spot of a cathode ray tube, said means including a camera tube and means for causing a luminous spot to appear sequentially in a plurality of predetermined discrete positions upon the screen of said tube, each position corresponding to a given character to be transmitted, and means for receiving said transmitted impulses.

8. System according to claim 1, wherein said pattern of characters covers substantially the entire surface of said code screen, so that said entire surface is utilized for communication.

9. System according to claim 1, in which said code screen is formed of material capable of transmitting light in at least a translucent manner, has said pattern of characters impressed thereupon in opaque form and is placed directly over the outer surface of said cathode ray tube screen, and also including an optical projection system, whereby said spot is optically projected upon said code screen at a predetermined point thereof, and whereby said pattern of characters is projected on said code screen, simultaneously with said spot.
